(57) **CLAIM**

The ornamental design for an entertainment system for an automobile headrest, as shown and described.

DESCRIPTION

FIG. 1 is a perspective view of view of an entertainment system for an automobile headrest showing my new design. FIG. 2 is a front view view thereof; and, FIG. 3 is a top view view thereof.

The broken lines shown in FIGS. 1-3 are for illustrative purposes only and form no part of the claimed design.
